UNITED STATES PATENT OFFICE.

WILLIAM THORNEY AND EMIL THORNEY, OF DENVER, COLORADO.

COMBUSTION-ENGINE.

1,103,451.

Specification of Letters Patent. Patented July 14, 1914.

Application filed May 14, 1913. Serial No. 767,728.

To all whom it may concern:

Be it known that we, WILLIAM THORNEY and EMIL THORNEY, citizens of the United States, residing at Denver, in the county of Denver, State of Colorado, have invented a new and useful Combustion-Engine, of which the following is a specification.

My invention relates to new and useful improvements in combustion engines and 10 more particularly to those in which a non-volatile fuel may be used.

The object of the invention is the provision of means whereby the non-volatile product is properly vaporized to successfully 15 operate the engine.

A further object is the provision of means for initially operating the engine with a volatile fuel until the non-volatile can be properly vaporized.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings:—Figure 1 is a side elevation of the engine. Fig. 2 is a detailed section of the connection for the non-volatile fuel.

In the drawings the letter A indicates a combustion engine of the well known construction having the carbureter 1, the inlet manifold 2 and the exhaust manifold 3 of ordinary construction. A supply pipe 4 leading from a supply of volatile fuel connects to the carbureter 1. A pipe 5 is connected to the inlet manifold and enters the exhaust manifold and passes through the exhaust as shown in dotted lines in Fig. 1. This pipe passes out of the exhaust as shown at 6 and to this pipe 6 is connected the supply of non-volatile fuel. An extension 7 is secured to the pipe 6 and passes up into and through the exhaust as shown in dotted lines; Fig. 1, and then passes out of the exhaust as shown at 8. The end 8 is open so as to allow air to pass freely into the pipe.

The non-volatile fuel is supplied by means of a pipe 9 which is connected to the cup 10 having the float regulating device 11 connected to the valve 12. A passage 13 leads from the cup 10 into the pipe 6. A screw

valve 14 is provided for cutting off the supply of non-volatile fuel to the pipe 6.

Surrounding the exhaust is a jacket 15 to which is secured a pipe 16 leading to the pipe connecting the carbureter 1 and inlet manifold 2. A lever 17 is provided for closing the end of the pipe 16 into the carbureter connection.

Having fully described my invention in detail I will now fully describe the operation. In starting the engine it is necessary to use the volatile fuel until the exhaust has become properly heated, to vaporize the non-volatile fuel. The supply of volatile fuel is then cut off and the valve 14 opened to allow the non-volatile fuel to pass from the cup 10 into the pipe 6. Air will enter the end 8 of the pipe 7 and will become heated before passing the fuel inlet. This air passing through the pipe 6 will suck the fuel from the cup spraying the same and properly vaporizing it. As the fuel passes through the pipe in the exhaust it will become properly vaporized to successfully operate the engine. By providing the jacket 15 and pipe 16 I can admit heated air into the manifold during the initial operation of the engine when the volatile fuel is being used.

Having fully described the invention what I claim as new and desire to secure by Letters Patent is:—

1. In combination with a combustion engine having a carbureter, an intake manifold and an exhaust manifold, a pipe connected to the intake manifold and passing through the exhaust, said pipe being open at the end outside of the exhaust, an extension on said pipe intermediate the ends extending outside of the exhaust, a supply of non-volatile fuel connected to said extension, and a supply of volatile fuel connected to the carbureter.

2. In combination with a combustion engine having a carbureter, an intake manifold, and an exhaust manifold, a pipe connected to the intake manifold and passing through the exhaust, an extension on said pipe intermediate the ends extending outside of the exhaust, a supply of non-volatile fuel connected to said extension, a pipe connected to the extension and passing through the exhaust, said pipe being open at the end outside of the exhaust, and a supply of volatile fuel connected to the carbureter.

3. In combination with a combustion en-

gine, having a carbureter, an intake manifold and exhaust manifold, a pipe connected to the intake manifold and passing through the exhaust, an extension on the pipe inter-
5 mediate the ends extending outside of the exhaust, a supply of non-volatile fuel connected to said extension, a pipe connected to the extension and passing through the exhaust, the end of said pipe being open out-
10 side the exhaust, a supply of volatile fuel connected to the carbureter, a jacket sur-

rounding the exhaust, and a pipe leading from the jacket to the intake manifold.

In testimony that we claim the foregoing as our own, we have hereto affixed our sig- 15 natures in the presence of two witnesses.

WILLIAM THORNEY.
EMIL THORNEY.
